UNITED STATES PATENT OFFICE

HEINZ KAHLHOFER, OF VIENNA, AUSTRIA

HOT AIR HAIR WAVING DEVICE

Application filed March 26, 1931, Serial No. 525,452, and in Austria August 3, 1929.

This invention relates to hair waving devices.

Hot air hair waving devices in which the hair curlers are heated by hot air conducted through heating chambers shut off from the curlers so that no hot air can stream over them, are known. The present invention relates to a novel method of constructing heating chambers in apparatus of this kind.

According to the invention the heating chamber is built up of a closed hollow body so shaped as to form a longitudinally extending recess adapted for receiving a curler so that the heating chamber may be pressed over the prepared hair curler.

A feature of the invention consists in the construction of the heating chamber in U section.

A further feature of the invention comprises a special arrangement of the interior of the heating chamber.

With the known devices, the hair is either pressed directly between the ribbed surfaces of the heating chambers, or, when curlers are used, it is pushed into the interior space of the tube-like heating chamber. The present invention, however, has the advantage over the known arrangements in that the heating chambers by reason of their special form may be pressed over the prepared curler and may be attached thereto by clips or the like. Further, the hot walls of the heating chamber lie adjacent to the hair curler nearly entirely around its outer surface so that the apparatus is much easier to handle than the known devices in which the curler is pushed into the heating body.

The invention is shown in the accompanying drawings wherein

Figure 1 is a section on the line 1-1 of Figure 2 showing only the hot air conduit.

Figure 2 is a section on the line 2-2 of Figure 3.

Figure 3 is a section on the line 3-3 of Figure 2.

The heating chamber 1 is built up of a closed hollow casing the shape of which being such that a longitudinally extending recess is formed. In the drawings I have shown a preferred construction of a heating

chamber 1 of U section into the interior space of which the curler 2 on the hair clip 3 is placed in such a manner that after preparation of the surface curler the heating chamber is pressed thereover. This heating chamber or hot air conduit consists of a pair of concentric walls 8 and 9, 8 being the inner wall and 9 the outer wall. These walls are spaced and the spaces between the end edges are closed by end walls 10 while the spaces between the side edges are closed by edge walls 11. The hollow space 4 of the closed heating chamber 1 is heated with hot air, the air streaming through the middle sleeve 5 into the middle of the chamber and divides 60 therein (see arrows) and leaves the chamber through the openings 6 at the ends thereof. For increasing the length of the heating air path the chamber is provided with intermediate walls 7 which reach nearly to the base. 70 The walls 7 form baffles and it will be noted that these walls are held between the central parts of the arcs of the walls 8 and 9, but that their ends terminate in spaced relation to the edge walls 11. By this means the air 75 enters the sleeve or inlet opening 5, flows down around the ends of the baffles 7 and then up to pass out of the outlet openings 6. Obviously the hot air will be kept constantly 80 flowing through the conduit while it is in use, so that the space within the inner wall 8 will be kept properly heated. By these means the heating medium is conducted along a devious path and a better warmth emission 85 is achieved.

The length of the heating chamber and the hollow space formed by its U section is greater than that of the curler so that this may be received in its entirety in the hollow 90 space.

What I claim is:

1. A heater for hair curlers consisting of a pair of spaced walls arcuate in cross section, the inner of said walls being imperforate throughout and the outer of said walls having a central inlet opening and a pair of outlet openings disposed each adjacent a respective end of the outer wall, end walls entirely closing the spaces between the ends of the concentric walls, edge walls entirely closing 100

the spaces between the lateral edges of the concentric walls, and baffles each located between the inlet opening and a respective outlet opening, said baffles each consisting of 5 an arcuate wall fixed between the middle portions of the arcs of the concentric walls and terminating in spaced relation to the edge walls.

2. The combination with a hair curler and 10 a flat clip member projecting at its side edges laterally beyond the curler on each side, of a hot air conduit of U-shaped cross section straddling the curler and having its side edges resting on the projecting portions of 15 the clip to form a curler chamber substantially semi-circular in cross section, said conduit having its inner face imperforate to prevent escape of air to the curler, said conduit further having inlet and outlet openings.
- 20 3. A heater for hair curlers consisting of a pair of spaced walls arcuate in cross section, the inner of said walls being imperforate throughout and the outer of said walls having a central inlet opening and a pair of 25 outlet openings disposed each adjacent a respective end of the outer wall, and walls entirely closing the spaces between the ends of the arcuate walls, and edge walls entirely closing the spaces between the lateral edges 30 of the arcuate walls.
